VAPOR PURIFICATION AND CRACKING
METHOD, AND APPARATUS, FOR PETRO-
LEUM OILS

Ernest A. Ocon, New York, N. Y.

Application June 15, 1935, Serial No. 26,835

16 Claims. (Cl. 196—61)

The object of the present invention is to provide a novel and efficient method for purification and cracking of petroleum oils, particularly adapted for oils high in sulfur and/or gum content.

In one phase of the method, the oil is initially raised in temperature until it is substantially vaporized and the vapors and unvaporized oil are simultaneously subjected to a treatment for reduction of viscosity, and the vapors are separated from the unvaporized oil simultaneously with a desulfurizing treatment, the vaporized product thus reduced in viscosity and substantially desulfurized is passed to two cracking coils receiving different degrees of thermal treatment, and in the coil receiving the highest thermal treatment, the said vapors meet the previously heated but unvaporized oil of the initial charging stock together with heavy liquid fractions remaining after the blending of vapors from the two cracking coils.

The blended vapors from both cracking coils, after desulfurizing treatment when the sulfur content of the original charging stock is high, or treatment by catalysts of the hydrogenation type if the sulfur content of the original charging stock is low, pass to a reaction chamber wherein the vapors are reduced in temperature, degummed and separated from heavier fractions, the vapors then passing to a final catalyst which may be of the desulfurizing type when required, or of the hydrogenating type when desulfurizing action is not required, the vapors then passing to a fractionating tower.

An anti-detonating material such as alkyl benzene, nitro-benzol, ethyl benzol, ethyl benzene, nitrous-ether, isopropyl benzene with alcohol in my preferred practice may be sprayed into the vapors, and in either vapor or liquid form, singly or in admixture.

In either phase of the invention where the breaking down of viscosity is not required and the sulfur content is low, the process is modified accordingly, the same principle applies to both phases, i. e., when the charging stock is vaporized and is led to a manifold from which two streams are led, each to an individual coil, the coil of highest heat receiving the unvaporized portions of the initial heated charging stock, the products discharged from both coils being blended, cooled, and subjected to catalytic treatment, and are degummed prior to fractionation where degumming is required, the cooling and degumming chamber being utilized as a separator for the heavy and condensed fractions which are led

back to the cracking coil of highest heat jointly with the originally heated but unvaporized charging stock.

The invention will be described with reference to the accompanying drawings, in which:

Figure 1 is a schematic view in elevation showing an apparatus for carrying the method into effect, and

Figure 2 is a view similar to Fig. 1, showing a modified form of the apparatus.

In the apparatus illustrated in the drawings, a charging stock is led by pipe 1 to a preheating coil 2 and thence to a second preheating coil 3, the heated charging stock passing into viscosity breaker tank 5.

Within tank 5 are baffles 6 below which there may be discharged from tank 7 a desulfurizing agent through pipe 8. Tank 5 receives a highly heated blast of cracked oil-steam vapors by means of a pipe 9 having a jet 10, the pipe communicating with the discharge outlet of a cracking coil later to be described.

Also within the viscosity breaker tank 5 near the top thereof may be a body of catalytic material 11 preferably of the desulfurizing type. By means of preheating coils 2 and 3, plus the heat added to tank 5 by the blast of highly heated vapors through jet member 10 and also external heat to be later described, the charging stock in tank 5 is raised to substantially vapor form. The vapors pass upwardly through desulfurizing material 11 and out through pipe 12, the unvaporized fractions dropping and being discharged as later to be described. The vapors reduced in viscosity by the heat treatment and the jet of oil steam vapors and the sulfur content being substantially reduced, leave pipe 12 and pass to a manifold 13. The upper end of the manifold discharges into a cracking coil 14, and the lower end of the manifold discharges into a cracking coil 14x, the cracking coils being disposed within a kln 4.

Steam is injected into the coils simultaneously with the pre-treated vapors by means of pipe 15 and branch pipe 17, 17x. The vapor temperature within the coil of highest heat, to wit, 14x, may be 1200-1400° F. and the vapor temperature in coil 14 may be 900-1200° F. Coil 14 at its discharge end may receive metallic catalyst 18 and coil 14x may receive metallic catalyst 18x. Adjacent the catalysts the coils have discharge branches communicating with a blending chamber 19 which may receive a sulfur reagent material through pipe 21 and a sulfur absorbent material through pipe 20.

Blending chamber 19 discharges directly into the lower section of a cooling and degumming chamber 22.

Referring to the drawings, it will be seen that the vapors flow in the direction of the arrows, first exterior to an inner cylindrical wall surrounding which is a body of gum adsorbent material 23, and thence downwardly into the inner cylindrical chamber, first passing through catalyzing material 24, thence in a circuitous path required by the baffles 24x, and thence being discharged by pipe 25 into the base of the fractionating tower 26.

The unvaporized treated oil is carried off through pipe 27x to the inlet of the coil of highest heat, 14x, and any heavy residue and spent sludge dropped to the bottom of tank 22 and are carried off by pipe 27 and branch pipe 44.

The fractionating tower may receive through a jet communicating with pipe 28 at the top of the tower an anti-detonating material in either liquid or vapor form such as one or a mixture of materials selected from alkyl benzene, nitro-benzol, ethyl benzol, ethyl benzene, nitrous-ether, iso-propyl benzene. The gasoline vapors leave the tower overhead through pipe 30, the light distillates leave the tower through pipes 31 and 32 and tower bottoms are withdrawn through pipe 33 by the action of pump 34 passing thence to a charging stock conduit, one being mixed with the charging stock about to pass through the preheater coil 3. Any sludge settling at the bottom of the tower 26 is ejected through pipe 37 and pipe 44.

The unvaporized heavy oil fractions within viscosity breaker tank 5 are withdrawn through pipe 38, trap 39 and pipe 38x to pump 40 which passes said heavy fractions substantially free from sludge, into the second trap 43 and thence to the coil receiving the highest degree of heat, 14x. Any sludge in trap 38 may be discharged through pipe 44x and in trap 43 may be discharged by means of pipe 44.

By means of branch pipe 36 suitably controlled by the valve, a small portion of the tower bottoms may be passed into the steam line 15.

In the practice of the method, treating of sulfur-containing oil, the charging stock is fed into the viscosity breaker 5 wherein a temperature of 500-750° F. may be maintained by the application of heat. The action of the preheating coils 2 and 3 will preheat the charging stock, for example, to 250° F. and this temperature will be raised in the viscosity breaker first by a blast of highly heated cracking oil-steam vapors and also, if required, a suitable heat application, as by passage of the products to the kiln through a chamber 46 surrounding the viscosity breaker. Thus the charging stock will be substantially 60 vaporized and its vapors will pass upwardly into contact with the catalytic material 11 which may be of the desulfurizing type, if required.

Preliminary to such catalytic treatment however, the vaporized charging stock is subjected to the action of sulfur adsorbent materials in liquid form, for example, ethylenediamine $C_2H_4(NH_2)_2$, tetrahydronaphthalene, triethanolamine $(C_2H_4OH)_3N$, ammonia NH_3 . Member 5 is not only a viscosity breaker but is a separation chamber by means of which the heavier unvaporized portion of the charging stock is separated from the vaporized portion. The vaporized portion of the charging stock which I prefer to be in much greater proportion, passes to a manifold preferably vertically arranged, communicating with

cracking coil 14 of lesser heat and cracking coil 14x of maximum heat, simultaneously. In other words, the vapors treated in the viscosity breaker may be split into two streams which simultaneously enter the cracking coils, one stream receiving higher heat treatment than the second stream. In or prior to entering the cracking coils the two streams of vapors receive steam from pipe 18 and also may receive a regulated flow of tower bottoms pumped through by-pass 36 into the steam coil 15. The temperature in the coil 14x of maximum heat may be 1200-1400° F. and in the coil of lesser heat 14, may be 900-1200° F. The discharge end of each coil may project exteriorly of the kiln and have disposed therein catalytic material 18, 18x, respectively, which may be of the hydrogenation type. These catalysts are not essential, however, in all cases.

From the discharge end of each coil the vapors enter into the blending section of a purifying chamber which in the drawings comprises section 19. Into the vapors within the blending section I inject (through pipe 21) a sulfur reagent material such as ammonium sulfide, ammonium chloride, zinc chloride in liquid or vapor form in order to accelerate the subsequent adsorption. Additional sulfur adsorbent material may be passed into the blending and purifying section (through pipe 28).

From the blending section the vapors are passed upwardly in chamber 22 through adsorbent material 23 which may be infusorial earth, fuller's earth, bauxite, silica gel, Florida earth, quartz, bentonite or other suitable material. The temperature of the vapors is lowered by radiation from the walls of members 19, 22, and by absorption by the heat exchange member 2. The vapors are purified and degummed by the adsorbent material 23 and the absorbed sulfur passes with the spent sludge to the base of tank 22, passing off through pipe 27. Level of the liquid in the lower portion of tank 22 is controlled by a valve near the top of pipe 27 so that there will be a constant flow of purified condensate, substantially free from tarry material, through pipe 27x to the cracking coil of highest heat.

The purified vapors leaving the adsorbent material 23 reach the top of the tank and pass through catalytic material 24, the catalysts used being one or a compound of two or more oxides and/or sulfides selected from metals such as tungsten, nickel, chromium, molybdenum, aluminum, titanium, magnesium, calcium, cobalt, zinc and the like. Iron sulfides, particularly the heavy metal sulfides, will advantageously be added to the catalysts which may be in any desired form such as beads, rings, baffles, wire gauze or in the form of lumps, briquettes, blocks, and may be mixed to a binder such as lime, clay, cement, and the like, and/or may be added advantageously to the charging stock in a finely divided form.

When the sulfur content is higher, the catalysts may be selected for desulfurizing properties. The cracked and purified vapors then pass into the fractionating tower and if necessary the temperature of the vapors may be raised and the vapors sweetened by the injection of steam into the base of the fractionating tower through pipe 28. As aforesaid, anti-detonating material may be injected into the vapors within the fractionating tower through pipe 30.

The vapors are fractionated and condensate may partly be used as fuel, as, for example, part

of the heavy condensate, or returned to the charging stock in the manner described above (pipe 33 and pump 34).

When desulfurization is not required, the use of the adsorbent and absorbent material may be changed accordingly, as well as the nature of the catalytic material. Thus catalysts 18, 18x, may be eliminated or be selected as of the hydrogenation type and one or more of the injection pipes 20 or 21 may be employed for the injection of purifying materials not of the desulfurizing type.

In the appended claims by "coil" is meant tubular structure of any form whether in single or multiple. It will also be understood that instead of injecting highly heated vapors from the cracking coil 14x into the viscosity breaker, I may employ highly heated material from a separate source.

It is to be noted that the steam injected into the intake end of each cracking coil may be superheated, as, for example, by means of a superheating coil 16 located directly within the cracking kiln. The manifold 13 may be of any desired diameter and of uniform diameter or of greater diameter in the section 13x.

Pressure upon one cracking coil may be varied with respect to the second coil by means of the valves 47x, 47xx. The cracking tubes may be of a length required for the general nature of the charging stock employed and the time of reaction may be controlled by the valves 47, 47x, so that the time of reaction in one coil may be greater or less than that of the second coil. The valves 35 in pipe 17, 17x may be manipulated to cause injection of more steam in one coil than in the second coil, as, for example, a greater proportion of steam may be injected into the coil 14x receiving the heavier materials, in each case 40 sufficient to retard polymerization of the oil vapors. The time of the cracking reactions of the oil-steam vapors will be less than thirty seconds, with pressure below 30 atmospheres, in the embodiment of the invention shown in the drawings. 45 In a plant of larger capacity the time of the cracking reactions will be correspondingly longer.

Having described my invention, what I claim and desire to secure by Letters Patent, is as follows:

50 1. In the art of cracking hydrocarbon oils, subjecting a petroleum stock to substantial vaporization and separating the vapors thus obtained from the unvaporized oil, dividing the vapors into a plurality of streams having the same 55 vaporization temperature and composition, subjecting each stream of vapor separately to cracking under pressure, one stream being subjected to cracking at a higher temperature than the other throughout its cracking reaction, and 60 subjecting the resultant cracked products, free of coke and tar, to fractionation.

2. In the art of cracking hydrocarbon oils, subjecting a petroleum stock to vaporization by heating the same to a mild cracking temperature of about 750° F. by applied heat including the heat of a blast of highly heated cracked oil vapors and steam, thus reducing the viscosity, separating the vapors thus obtained from the unvaporized oil, and simultaneously dividing the 65 vapors into two streams, subjecting each stream of vapor separately to a higher cracking temperature than that of the original mild cracking temperature, and not exceeding 1400° F., for a time sufficient to substantially crack said stream, under pressure, one stream being subjected to tem-

perature substantially higher than the temperature applied to the other stream, and subjecting the resultant clean cracked products to fractionation.

3. A process in accordance with claim 2, in which the vapors during treatment to reduce viscosity are subjected to the action of a desulfurizing absorbent in the presence of a catalyst, for the absorption of sulfur released below cracking temperatures, and after leaving the cracking coils the cracked vapors are subjected to the action of desulfurizing materials within the blending zone, said materials being of the type adapted for sulfur precipitation under cracking temperatures of the oil vapors, and thence fractionating the cracked and desulfurized vapors.

4. A process in accordance with claim 2, in which superheated steam admixed with a small quantity of hydrocarbon oil is injected into the vapor streams entering the cracking coils.

5. In the art of cracking hydrocarbon oils, subjecting a petroleum charging stock to substantial vaporization and separating the liquid from the vapor, directing the vapor into two streams, and leading each stream through a cracking coil, one coil being subjected to higher temperature than the second coil, leading the cracked vapors to a blending zone, cooling the vapors and passing them through a zone containing sulfur absorbent material, separating the condensate from the zone of cooling, recycling the condensate through the coil of higher temperature jointly with vapors from the initial charging stock, and fractionating the thus cracked, blended and treated vapors.

6. A process in accordance with claim 5, in which the tower bottoms from the fractionating zone are recycled by passing them into the charging stock stream, and thence with the charging stock into the vaporization zone preceding the cracking coils.

7. In the art of cracking hydrocarbon oils, subjecting a petroleum stock to substantial vaporization, separating the liquid from the vapor in the viscosity reducing zone wherein highly heated steam-oil vapors are led, passing into the viscosity reducing zone a sulfur absorbent material, passing the said separated charging stock vapors to a separating column having two outlets, each being connected to a cracking coil whereby the two streams of vapors are led through the cracking coils, one coil being subjected to a higher temperature than the second coil, discharging the cracked vapors from the coils into a blending zone, injecting into the blending zone a desulfurizing absorbent operable at cracking temperature of the charging stock vapors, and thence passing the cracked, blended and desulfurized vapors into a fractionating tower, and passing the liquid from the viscosity reducing zone into the cracking coil of higher temperature jointly with the treated vapors from said viscosity reducing zone.

8. In the art of cracking hydrocarbon oils, subjecting a petroleum charging stock to substantial vaporization, separating the liquid from the vapor, dividing the vapor into two streams, subjecting both streams of vapor simultaneously to cracking, one stream being subjected to a higher temperature than the second stream, blending the cracked vapors from both streams and leading the cracked and blended vapors to a fractionation zone wherein said vapors are subjected to a prepared synthetic liquid spray of anti-detonating material, for common condensation, said liquid spray being injected into the upper

part of said fractionating zone in a direction countercurrent to the movement of the vapors.

9. In apparatus for treating hydrocarbon oils, means for substantially vaporizing a charging stock, a viscosity breaker communicating with said means, a plurality of cracking coils, means for injecting steam into each of said coils, means for leading highly heated steam-oil vapors from one of said cracking coils to the viscosity breaker, means for leading liquid from the viscosity breaker to the last named coil, means for heating the last-named coil to a cracking temperature in excess of heat applied to the other coil, a manifold having separate discharge outlets each connected with one coil, a vapor flow connection from the viscosity breaker to said manifold, a blending chamber receiving cracked vapors from the coils, means for injecting a sulfur absorbent material into said blending chamber, a purifying chamber receiving the cracked and blended vapors from the blending chamber and having therein means for cooling the vapors together with adsorbent material through which the vapors are caused to flow, and a fractionating tower receiving the treated vapors from the purifying chamber.

10. Apparatus constructed in accordance with claim 9, in which the cracking coils are provided with sections projecting laterally of the heating zone for said coils, metallic catalysts of the hydrogenation type disposed within said projected sections, and connections between said projected sections and the blending chamber.

11. Apparatus constructed in accordance with claim 9, in combination with means for conveying tower bottom to the charging stock stream in the passage of the latter to the viscosity breaker.

12. In a process for the production of motor fuel, subjecting a hydrocarbon stock to vaporization and cracking, subjecting the vapors to desulfurizing and degumming action, separating the vapors of gasoline boiling range from the heavier vapors, mixing the gasoline boiling range vapors with a prepared synthetic highly volatile anti-detonating material without substantially condensing said vapors, and condensing the said gasoline vapors with the anti-detonating material mixed therewith, to produce a purified homogeneous anti-detonating motor fuel.

13. A process for producing hydrocarbon products of low boiling point from high boiling point liquid hydrocarbons which comprises, subjecting the initial charging stock to contact with a blast of highly heated vapors in a vaporizing zone to vaporize a portion of the charging stock, subjecting unvaporized portions of the charging stock to heat and heating said portions at cracking temperatures while in a flowing stream in the presence of steam to release and form hydro-

carbon vapors, passing thus produced vapors jointly with steam to the vaporization zone to act as a blast of highly heated vapors, withdrawing mixed vapors from the vaporization zone and subjecting them to cracking in a separate cracking zone.

14. In the art of cracking hydrocarbon oils, subjecting a petroleum stock to substantial vaporization and separating the vapors thus obtained from the unvaporized oil, subjecting the vapors to the action of a desulfurizing absorbent for the absorption of sulfur released below cracking temperatures, dividing the vapors into a plurality of streams having the same vaporization temperature and composition, subjecting each stream of vapor separately to cracking under pressure, one stream being subjected to cracking at a higher temperature than the other throughout its cracking reaction, mixing the two cracked vapor streams, subjecting said mixture of vapors to the action of desulfurizing materials, said materials being of the type adapted for desulfurization of oil vapors under cracking temperatures of the oil vapors, and thence fractionating the cracked and desulfurized vapors.

15. In the art of cracking hydrocarbon oils, the steps of preheating the hydrocarbon oils, subjecting the preheated oils to substantial vaporization in a zone wherein a blast of highly heated cracked hydrocarbon vapors obtained in the cracking of the oils during the process is injected in a direction countercurrent to the passage of the preheated oils, producing a mixture of cracked and uncracked vapors, separating the vapors thus obtained from residue and tarry material, mixing the vapors with steam, subjecting the mixture, with increase of heat, to cracking, by passing a stream of said mixture through a coil subjected to heat above the critical cracking temperature of the mixture and wherein said mixture is progressively heated to a maximum, not exceeding 1400° F., under pressure, the mixture reaching its highest temperature at the outlet of the coil, passing said mixture at its highest temperature over an hydrogenating catalyst, and subjecting said treated vapors to fractionation.

16. A process of producing hydrocarbon products in accordance with claim 13 in which part of the mixed vapors are separated from the remaining part and are cracked in a cracking zone separate from that in which said remaining part of mixed vapors are progressively heated to effect substantial cracking thereof, under superatmospheric pressure range below thirty atmospheres and subjected to a cracking temperature below 1400° F. and resulting products are used as part of the blast of highly heated vapors injected into the expansion zone.

ERNEST A. OCON.
